UNITED STATES PATENT OFFICE.

LOUIS BURGER, OF CHICAGO, ILLINOIS.

DESIGN FOR A MATCH-SAFE.

SPECIFICATION forming part of Design No. 22,366, dated April 25, 1893.

Application filed February 28, 1893. Serial No. 464,113. Term of patent 3½ years.

To all whom it may concern:

Be it known that I, LOUIS BURGER, a citizen of the United States, residing at Chicago, in the county of Cook and State of Illinois, 5 have invented and produced a new and original Design for Match-Safes, of which the following is a description.

The drawing illustrates the front and rear sides of a match safe supplied with my design.

The leading feature of my design consists in the upper rounded lid portion, which has marked thereon a representation of a part of the configuration of the earth and in the 15 body portion, one face of which has marked thereon the representation of the head of Columbus, and the other face of which has marked thereon the representation of Queen

Isabella. The face carrying the representation of Queen Isabella is shown in the drawing as having marked thereon representations of flags, the staffs of which afford a frame outline for the picture of Queen Isabella, and beneath the picture is shown a representation of a World's Fair building. Queen Isabella is 20 25 illustrated as holding in her hands a casket of jewels.

What I claim as new, and desire to secure by Letters Patent, is—

The design for a match safe substantially 30 as herein shown and described.

LOUIS BURGER.

In presence of—

M. J. FROST,
W. N. WILLIAMS.
